US00D696544S

(12) **United States Design Patent**
Smith et al.

(10) **Patent No.:** US D696,544 S
(45) **Date of Patent:** ** Dec. 31, 2013

(54) **CHAIR**

(71) Applicant: **Steelcase Inc.**, Grand Rapids, MI (US)

(72) Inventors: **Bruce M. Smith**, East Grand Rapids, MI (US); **Glen Oliver Low**, Hamburg (DE); **James N. Ludwig**, East Grand Rapids, MI (US); **Robert J. Battey**, Middleville, MI (US); **Gordon Jay Peterson**, Rockford, MI (US)

(73) Assignee: **Steelcase Inc.**, Grand Rapids, MI (US)

(**) Term: **14 Years**

(21) Appl. No.: **29/449,641**

(22) Filed: **Mar. 15, 2013**

Related U.S. Application Data

(63) Continuation of application No. 29/432,775, filed on Sep. 20, 2012.

(51) **LOC (9) Cl.** **06-01**

(52) **U.S. Cl.**

USPC **D6/716.4**

(57) **CLAIM**

We claim the ornamental design for the chair, as shown and described.

DESCRIPTION

FIG. 1 is a perspective view of a chair embodying the present invention;

FIG. 2 is a front view of the chair;

FIG. 3 is a first side view of the chair;

FIG. 4 is a second side view of the chair;

FIG. 5 is a rear view of the chair;

FIG. 6 is a top view of the chair; and,

FIG. 7 is a bottom view of the chair.

The broken lines shown in the drawing are for illustrative purposes only and form no part of the claimed design.
